(57) **CLAIM**

The ornamental design for a cable management skirt, substantially as shown and described.

DESCRIPTION

FIG. 1 is a perspective view of a cable management skirt, showing our new design;

FIG. 2 is a top view thereof;

FIG. 3 is a bottom view thereof;

FIG. 4 is a first side view thereof;

FIG. 5 is a second side view thereof;

FIG. 6 is a back view thereof; and

FIG. 7 is a front view thereof; and,

FIG. 8 shows the cable management skirt in environment. The broken lines in the figures illustrate environment that form no part of the claimed design. The Applicant reserves the right to claim a portion of the designs in this or a continuing application by changing solid lines to broken lines and/or broken lines to solid lines. For example, a claim can be made to a portion of the cable management skirt of FIGS. 1–7, rather than to the entirety of the cable management skirt of FIGS. 1–7.
